ERNEST S. BOWEN, OF GENEVA, NEW YORK, ASSIGNOR OF ONE-HALF TO WALTER LESTER FAY, OF GENEVA, NEW YORK.

EXPLOSIVE-ENGINE.

961,581.

Specification of Letters Patent. Patented June 14, 1910.

Application filed November 16, 1907. Serial No. 402,452.

To all whom it may concern: .

Be it known that I, ERNEST S. BOWEN, a citizen of the United States, residing at Geneva, in the county of Ontario and State 5 of New York, have invented new and useful Improvements in Explosive-Engines, of which the following is a specification.

My invention relates to explosive engines adapted to be operated by kerosene 10 and other liquids, which are more difficult to vaporize than gasoline, and cannot be vaporized properly without being heated.

In the construction of engine here shown, either gasoline or kerosene may be used. 15 One of its important features consists in the simple modification and arrangement of parts by which the kerosene is heated so as to be easily and sufficiently vaporized, then at once introduced into the cylinder, and 20 maintained sufficiently hot until ignited. A vaporizing chamber is arranged at some convenient point on the exterior of the cylinder. The compressed air is forced into said chamber through a suitable channel from the 25 crank case; a second channel is provided to conduct the vapor from said chamber into the cylinder. The exhaust pipe for the hot exhaust gases is arranged to pass through said chamber; the fuel inlet is arranged in 30 the upper portion of the chamber so that the kerosene will initially fall on the hot exhaust pipe, thus promoting the vaporizing of the kerosene, and insuring the production of a vapor in such a physical condition that 35 it can be ignited by the electric spark.

My invention is fully illustrated in the drawing herewith in which the reference figures of the description indicate the corresponding parts in all the figures.

40 Figure 1 is a vertical cross section, through a cylinder of an engine made according to my invention, adapted for the use of kerosene or gasoline at will. Fig. 2 is a section on line 2-2 of Fig. 1. Fig. 3 is a partial 45 front elevation of Figs. 1 and 2.

In the figures 1 indicates the crank-case, supported on a suitable base 3.

4 is the crank-shaft connected to the piston 6 by the crank 7, the crank-pin 8 and the 50 pitman 9.

10 is the cylinder having the inlet or intake ports 11, and the exhaust ports 12.

15 is a casting, or jacket, bolted to a suit-

able seat 16 on the front of the cylinder, and forming the vaporizing chamber 17, which 55 is connected by the by-pass channel 18 to the interior of the crank-case, and by the upper by-pass channel 19 to the intake ports 11. In the upper portion of said jacket is arranged the needle-valve 21, to which the 60 kerosene is conducted, preferably under a pressure of a few pounds, through the kero- 65 sene supply pipe 22, from any suitable reser- 70 voir. The amount of liquid fuel is regu- lated by the needle valve. From the ex- 75 haust-port extends the curved exhaust pipe 24 around the front of the engine as shown, and through the vaporizing chamber, under the needle valve.

25 is a screw plug removable, when it is 75 desired initially to heat the exhaust pipe without the use of gasoline, as by a torch.

The other parts shown are the air inlet 75 pipe 30 to the carburetor, or gasoline vapo- 80 rizer 31. 32 is the pipe from said vaporizer 85 to the crank-case.

33 is the gasoline supply pipe and 34 the gasoline needle valve.

The terminals and means for accelerating 80 and retarding the spark are merely indi- 85 cated. These may be of the construction shown in my Patent No. 711,652 or of other suitable construction. 40 is the fixed and uninsulated terminal; 41 is the moving in- 90 sulated terminal. On the pin of the latter 95 is an arm struck by a plunger to draw the spark. These parts are carried on a re- 100 movable pin 44. The plunger is moved by the cam 46, which is rotated by the cam- 105 shaft through the igniter-shaft 47 and suit- 110 able connections. This cam may be shifted by the handle 48 to retard or accelerate the 115 spark.

50 is a priming cock in the cylinder head.

I have thus produced, merely by the addi- 95 tion of the kerosene vaporizer and the ar- 100 rangement of the exhaust pipe, an engine which may be operated by kerosene, alcohol, etc., or in the usual manner by gasoline.

When running on kerosene, the air is first 100 drawn into the crank-case through the gaso- 105 lene vaporizer and pipes 30-32; the air is then compressed on the down-stroke of the piston, and when the piston has uncovered the intake ports 11, is forced through the 110 lower channel 18 to the vaporizing chamber 115

17, where it is mixed with the proper quantity of vaporized fuel and thence through the upper channel 19 to the cylinder; here the mixture is compressed on the return up-
5 stroke of the piston, and then ignited by the spark in the explosion chamber, or upper portion of the cylinder.

The exhaust heats the exhaust pipe, whereby it is possible so to vaporize the kerosene
10 that the vapor can be ignited by the spark. This is an important feature of my invention, for the spark can thus be set ahead to generate high power as where gasoline is used. Another important feature is the ar-
15 rangement of parts described, that is, the providing of distinct and separate vaporizers for the two kinds of fuel, and the spraying of the kerosene on to the hot ex-
haust-pipe, for perfect vaporizing, and not
20 directly into the ignition chamber. When the kerosene has been vaporized, it is at once injected into the hot explosion chamber, so that there is no chance of its reliquefying. If any portion should so reliquify, it would
25 not only weaken the charge, but would tend to flood the engine.

I am aware, that it has heretofore been known that kerosene and alcohol were harder to vaporize than gasoline and that
30 explosive engines have been constructed for use with kerosene, but these were essentially different in construction and arrangement of parts from mine, and, so far as I am aware, the vapor was ignited by a bulb, or
35 other part, maintained red-hot, in the top of the cylinder. With such an arrangement, practically the only way to vary the speed is to vary the amount of kerosene, and this is uncertain as it involves the regulating ex-
40 actly the length of stroke of a pump, and that where a most trifling quantity of fuel is being delivered at each stroke.

It will be understood that in starting the engine, the exhaust pipe must first be heated
45 to insure the vaporizing of the kerosene in its vaporizing chamber. This may be done as suggested by introducing the torch through the hole of the plug 25 and holding it under the exhaust pipe for a minute or
50 two, more or less. Or the engine can be started by priming the cylinders with a little gasoline from a squirt-can through the priming cock 50. Or the engine may first be operated a few turns by gasoline in the usual manner through the gasoline vaporizers; then shut off the gasoline and turn on the kerosene.

I have shown here a single cylinder only, and a two cycle engine, but it will be evident that my invention can be applied to a four cycle engine and to an engine having as many cylinders as may be desirable. Those are usual changes in gas-engines and no further explanation is necessary.

65 Having thus described my invention,

what I claim, and desire to secure by Letters Patent, is—

1. In an explosive, or gas engine the combination with the crank-case, the cylinder thereon, the shaft journaled in the crank case, the piston and crank and pitman connecting the piston to the shaft, said cylinder being supplied with intake and exhaust ports, a gasoline vaporizing chamber arranged on the crank-case, a pipe from said chamber to the crank-case, a supply pipe to said chamber, a needle-valve in said pipe, an air-inlet pipe to the carbureter, a kerosene vaporizing chamber secured on the cylinder, a supply pipe to said kerosene vaporizing chamber, a needle valve in said kerosene supply pipe, means arranged in said kerosene vaporizing chamber to heat the kerosene as it enters, a lower by-pass channel from the crank case to the kerosene vaporizing chamber and an upper by-pass channel from the kerosene vaporizing chamber to the intake ports.

2. In an internal combustion engine adapted to be operated by liquid fuels which are more difficult to vaporize than gasoline, the combination with the piston the crank-case and the cylinder having substantially opposite intake and exhaust ports in its lower portion, of an exterior shell or casting secured to the front of the cylinder to form a vaporizing chamber for the fuel, an exhaust pipe connected to the exhaust ports and arranged to pass through the chamber, a fuel supply pipe connected to the chamber at a point above the exhaust pipe, a needle valve in the supply pipe, a removable screw-plug fitted to the front of the chamber, an air pipe to the crank-case, a channel from the crank-case to said chamber and a channel from said chamber to the intake ports.

3. In an internal combustion engine in which the air is compressed before entering the cylinder, the combination with the cylinder having intake and exhaust ports and the piston operating within the cylinder, said cylinder being formed with a passage for the compressed air to the intake port, of a shell forming a vaporizing chamber in said passage, a pipe from the exhaust port passing through said chamber and means to supply liquid fuel to said chamber to be vaporized by contact with said pipe, and to be introduced in mixture with the compressed air to the cylinder.

4. In an internal combustion engine in which the air is compressed before entering the cylinder, the combination with the crank case, the cylinder having intake and exhaust ports and the piston operating within the cylinder, said cylinder being formed with a passage in its wall from the crank case to the intake port for the compressed air, of a shell forming a vaporizing chamber in said

passage, a pipe from the exhaust port passing through said chamber and means to supply liquid fuel to said chamber to be vaporized by contract with said pipe and to be introduced in mixture with the compressed air to the cylinder.

In testimony whereof I have signed my

name to this specification in the presence of two subscribing witnesses.

ERNEST S. BOWEN.
